UNITED STATES PATENT OFFICE.

CHARLES H. ANDERSON, OF LEXINGTON, KENTUCKY.

APPARATUS FOR FEEDING LIQUID FUEL TO CARBURETERS.

1,328,354.

Specification of Letters Patent.

Patented Jan. 20, 1920.

Application filed January 17, 1919. Serial No. 271,649.

To all whom it may concern:

Be it known that I, CHARLES H. ANDERSON, a citizen of the United States, and a resident of Lexington, in the county of Fayette and State of Kentucky, have invented certain new and useful Improvements in Apparatus for Feeding Liquid Fuel to Carbureters; and I do hereby declare the following to be a full, clear, and exact description of the invention, such as will enable others skilled in the art to which it app pertains to make and use the same.

My invention relates to an improvement in apparatus for feeding liquid fuel to carbureters, to provide a liquid fuel feed system in which the fuel is drawn from a main tank by suction and fed to the carbureter by gravity.

With this object in view my invention consists in the parts and combinations of parts as will be more fully explained and pointed out in the claims.

In the accompanying drawings; Figure 1 is a view of the auxiliary tank connected with the suction pipe of an internal combustion engine, the suction pipe being in section; Fig. 2 is a view in section of the auxiliary tank; Fig. 3 is a plan of the tank the top of the latter being removed; Fig. 4 is a view similar to Fig. 2 of a modification and Fig. 5 is a diagrammatic view of the two tanks and suction pipe of an engine.

4 represents a tank preferably made of sheet metal, permanently closed at one end provided at its other end with a removable head 5. The head is provided centrally with the combined coupling and valve seat 6, which is coupled by a pipe to the main gasoline supply 4^a and is provided adjacent its inner end with a seat for the needle valve 8. The needle valve passes upwardly through the tank 4 and is provided at its upper end with a grooved collar 9, the groove of which receives the inner ends of the weighted levers 10 which are pivoted to the head 11 secured to the upper end of the tube 12. This tube is secured at its lower end in the coupling 6, and embraces the valve 8; is of greater internal diameter than the valve so that the gasoline or other liquid can pass freely up and around the valve, and is provided adjacent its upper end with holes 13 through which the gasoline passes into the tank.

Surrounding the tube 12 and freely movable thereon is the float 14, which is so lo-

cated with relation to the levers 10 that when the float rises, it engages the outer weighted ends of the said levers and lifts them and correspondingly depresses their inner ends, which being in engagement with the collar 9 on the needle valve 8, forces the latter downwardly and closes the liquid inlet opening, the levers being maintained in a position to properly engage the float by the head 11 on which they rest when the float is down.

Secured to one side of the tank is a coupling 15, connected externally by pipe 16 with the suction pipe 16^a or manifold of a gasoline engine, and communicating internally with pipe 17 which extends up into the tank above the highest level of gasoline therein, the said level being indicated by a dotted line.

Secured to the side of the tank below the normal liquid level is the coupling 18, provided internally with the outlet pipe 19, which terminates below the normal liquid level, and provided externally with the pipe 20 which leads to the spray nozzle 20^a in the suction pipe 16^a of the engine for supplying gasoline to the latter.

In the construction shown in Fig. 1, the feed from the spray nozzle 20^a has a needle valve 21 which regulates the supply of gasoline to the carbureter or suction pipe and when this valve is closed the supply through pipe 20 stops.

The pipes 16 and 20 are both connected to the carbureter or suction pipe of the engine between the latter and the butterfly or throttle valve 22, hence when the engine is running the suction in the suction pipe 16^a acting through pipes 16 and 17 and coupling 15, will create a partial vacuum in the tank 4 which operates to draw in the gasoline through coupling 6 from the main tank. As the gasoline fills the tank the float rises and by its engagement with the levers 10 closes valve 8 and cuts off the supply when the float reaches its normal level. As both pipes 16 and 20 are connected with the suction pipe of the engine between the latter and the throttle valve, there will also be a suction through pipe 20 equal to that in pipe 16, so that the suction through both pipes, above and below the gasoline, will be balanced, with the result that gasoline will be drawn through pipe 20 and fed to the spray nozzle so long as the needle valve of the latter remains open. When it is closed,

the engine stops, hence while the engine is working the vacuum created by the suction through pipes 16 and 17 draws in the gasoline from the main supply tank, while the 5 suction through pipe 20 feeds the gasoline from the auxiliary tank to the carbureter.

The construction above described is particularly adapted for use with carbureters having an automatic regulator and cut off 10 for the gasoline as disclosed in my application Serial No. 271,648 filed Jan. 17, 1919. In Fig. 4 I have shown a construction in which the supply of gasoline to the pipe leading to the carbureter or spray nozzle is 15 automatically cut off as soon as the engine is stopped, thus adapting it among other things for use with a carbureter having a regulating valve but no cut off valve.

In Fig. 4 the coupling 18^a is provided with 20 a seat for the valve 18^b on the lower end of the rod 18^c. This rod extends upwardly to a point above the normal level of the gasoline in tank 4, and through a long sleeve 18^d which preferably extends below the normal 25 liquid level for preventing the entrance of any air to the vacuum space above the liquid, and is provided at a point above the top of the tank with a diaphragm 18^e secured at its edges within the chamber 18^f. The portion of the chamber below the diaphragm is open to the outer air, while the 30 part thereof above the diaphragm is connected by port 18^g with the upper part of tank 4. With this construction when the 35 engine is working, the vacuum in the upper part of tank 4 lifts the diaphragm and the valve 18^b connected therewith and permits of the free flow of oil to the carbureter. When the engine stops and the vacuum is 40 broken as previously explained, the diaphragm and its connected valve drop thus shutting off the supply of oil to the carbureter.

With these constructions, by arranging 45 the two pipe connections with the suction pipe of the engine between the engine and the throttle valve, suction on the fuel in the tank and in the outlet or nozzle pipe will be balanced thus leaving the gasoline free to 50 flow out under any head in the auxiliary tank.

It is evident that many slight changes might be resorted to in the relative arrangement of parts shown and described without 55 departing from the spirit and scope of my invention, hence I would have it understood that I do not wish to confine myself to the exact construction and arrangement of parts shown and described, but

60 Having fully described my invention what I claim as new and desire to secure by Letters Patent, is:—

1. In a vacuum feed for internal combustion engines, the combination of a fuel tank 65 having a pipe connection above and a pipe

connection below the normal fuel level in the tank, with the suction pipe of the engine and at the same side of the throttle valve in the suction pipe, whereby the vacuum in the two pipe connections with the 70 suction pipe will be balanced, a spray nozzle in the suction pipe and connected with the fuel pipe leading from below the fuel level in the tank, and means actuated by the suction for controlling the supply of fuel to 75 the suction pipe through the spray nozzle.

2. In a vacuum fuel system for internal combustion engines, the combination of an auxiliary fuel tank having a connection with the main tank, an automatic valve for controlling the supply from the main tank to the auxiliary tank, two pipe connections from the auxiliary tank to the suction pipe of the engine, one of said pipe connections leading from the auxiliary tank above the 80 normal fuel level in the latter for creating a vacuum in the tank, and the other pipe connection leading from the tank below the normal fuel level, a spray nozzle located in the suction pipe with its discharge end in a 85 plane below the normal fuel level of the fuel in the auxiliary tank, the said nozzle being connected with said last mentioned pipe and a valve actuated by the suction for controlling the supply of fuel passing through the 90 spray nozzle to the suction pipe.

3. In a vacuum feed system for internal combustion engines, the combination of an auxiliary fuel tank having automatic valve arrangement for controlling the feed of fuel 100 from the main tank to the auxiliary tank, a suction pipe having a fluid discharge nozzle therein, a pipe connection leading from the auxiliary tank below the normal fluid level in the auxiliary tank to said nozzle, a pipe 105 connection leading from the upper part of the auxiliary tank to the suction pipe, the two pipe connections with the suction pipe being between the engine and the throttle valve in the suction pipe whereby the fuel 110 in tank and nozzle pipe will be balanced and free to flow under the head of oil in the auxiliary tank, and a valve actuated by the suction for controlling the supply of fuel passing through the spray nozzle to the suction 115 pipe.

4. In a vacuum feed system for internal combustion engines, the combination of a suction pipe having a fuel nozzle therein, an auxiliary fuel tank so located that its 120 normal fluid level is in a plane above the nozzle, a pipe connection from said tank and below the normal fluid level with said nozzle, a pipe connection between said suction pipe and the tank above the normal 125 fluid level, the said latter pipe connection with the suction pipe and the nozzle being between the engine and the throttle valve in the suction pipe whereby the suction at the nozzle and the suction above the oil in 130

the auxiliary tank will be balanced, a pipe connection from said tank to a main supply tank, an automatic valve for regulating the feed from the main tank to the auxiliary tank and a valve operated by the suction for controlling the supply of fuel passing through the spray nozzle to the suction pipe.

In testimony whereof, I have signed this specification in the presence of two subscribing witnesses.

CHARLES H. ANDERSON.
